UNITED STATES PATENT OFFICE

LYLE B. SHINN, OF CHICAGO, ILLINOIS, ASSIGNOR TO CHICAGO LOCK COMPANY, OF CHICAGO, ILLINOIS, A CORPORATION OF ILLINOIS

LOCK

Application filed July 19, 1930. Serial No. 469,083.

The present invention relates generally to locks. More particularly the invention relates to that type of lock which is designed for use in connection with the ignition switch, transmission, spare tire carrier or doors of an automobile, and comprises (1) a cylindrical casing which is adapted to be mounted fixedly in place; (2) a plug which is rotatable in the casing and has transversely extending slideways in the inner portion thereof; (3) a plurality of tumblers which are stamped from sheet metal, fit slidably in the slideways and have central slots therein through which the key for the lock is adapted to pass; (4) springs which are disposed in recesses or sockets at the sides of the slideways and operate to force the tumblers towards the casing; and (5) a device or element at the inner end of the plug which operates to permit the plug to be withdrawn from the casing so that it may be repaired or another plug with a different key combination may be substituted in its stead.

One object of the invention is to provide a lock of the aforementioned type in which the key-operable tumblers are provided with improved means whereby they are held in connected relation with respect to the plug and are prevented from being ejected from the slideways by the springs when the plug is removed from the casing for repair or replacement purposes.

Another object of the invention is to provide a lock of the type hereunder consideration in which the holding means for preventing ejection of the tumblers from the slideways in the plug consists of tongues which are formed integrally with and project outwardly from the tumblers and coact with the lugs for guiding the key through the interior of the plug.

A further object of the invention is to provide an automobile lock which is generally of new and improved construction, may be manufactured at a comparatively low cost and is an improvement upon previously designed locks of a similar character.

Other objects of the invention and the

various advantages and characteristics of the present lock construction will be apparent from a consideration of the following detailed description.

The invention consists in the several novel features which are hereinafter set forth and are more particularly defined by the claims at the conclusion hereof.

In the drawings which accompany and form a part of this specification or disclosure and in which like numerals of reference denote corresponding parts throughout the several views:

Figure 1 is a perspective view of a lock embodying the invention, the plug and casing being shown in disconnected relation for purposes of illustration;

Figure 2 is a vertical longitudinal section, showing in detail the manner in which the tongues on the tumblers coact with the guide lugs for the key to hold the tumblers against displacement with respect to the slideways;

Figure 3 is a vertical transverse sectional view taken on the line 3-3 of Figure 2 and exhibiting in detail the cross sectional construction of the plug and the manner in which the springs operate to urge or force outwardly the tumblers;

Figure 4 is a bottom view of the plug;

Figure 5 is a perspective of one of the key-operable tumblers; and

Figure 6 is a cross sectional view of the plug, showing the key for the lock in the plug.

The lock which forms the subject matter of the invention is designed primarily to be used in connection with any of the various elements of an automobile which are to be lock-controlled, such, for example, as the ignition switch, transmission or spare tire carrier. It comprises a cylindrical casing 7 and a plug 8. The casing is adapted to be built into or formed integrally with the element that is to be lock-controlled, and has formed in the central portion thereof a longitudinally extending bore 9. The plug 8 is shaped so that it is insertable into and rotatable in the bore 9. The outer or front end of the plug is provided with an enlarged circular head 10. This head fits in

an annular recess 11 which is formed in the outer or front end of the casing 7 and is slightly larger in diameter than the bore 9. An annular recess 12 is formed in the inner or rear end of the casing. This recess is substantially equal in diameter to the recess 11 and is defined at its front end by an annular shoulder 13. A slot 14 for receiving a key 15 extends longitudinally through the central portion of the plug.

In addition to the casing 7 and the plug 8, the lock comprises a plurality or set of key-operable tumblers 16 and a special tumbler 17. The key-operable tumblers 16 are stamped from sheet metal and operate to lock the plug against rotation in the casing. They are carried by the plug rearwardly of the head 10 and are mounted slidably in transversely extending slideways 18. The latter intersect the key slot 14 and extend completely through the plug, as illustrated in Figure 2. Each of the tumblers 16 consists of a pair of side bars 16^a, an end bar 16^b and an end bar 16^c which together form a central slot 16^d through which the key 15 is adapted to pass. When the key 15 is inserted into the plug, the tumblers 16 are shifted so that the end bars 16^b and 16^c are aligned with the periphery of the plug and thus permit the plug to be rotated into and out of its locked position. The tumblers are pressed outwardly with respect to the plug by means of springs 19. These springs are disposed in sockets 20 and abut against ears 21 which are formed integrally with and project laterally from the tumblers. The sockets 20 communicate with the slideways 18, as illustrated in Figures 3 and 4. The casing 7 is provided along the bore 9 with a longitudinally extending groove 22 into which the end bars 16^b of the tumblers are forced by the springs 19 so as to lock the plug against rotation. When the key 15 is inserted into the key slot 14, the end bars 16^c of the tumblers are engaged by the notched portion of the key and are shifted so as to bring the tumblers into a position wherein the end bars 16^b are withdrawn from the groove 22. In this position of the tumblers the plug is free so that it may be rotated out of its locked position by the key. In addition to the longitudinal groove 22, the casing has formed therein a longitudinally extending groove 23. This groove is positioned diametrically opposite the groove 22 and is adapted to receive the end bars 16^b of the tumblers when the key 15 is withdrawn after it is used to rotate the plug into its unlocked position. The front ends of the grooves 22 and 23 communicate with the annular recess 11 at the front end of the casing so that the plug may be inserted into the casing and removed therefrom for repair or replacement purposes. The key 15 is guided into and out of the plug by a series

of lugs 24. These lugs are disposed at one side of the key slot 14 and are formed integrally with the portions of the plug that define the slideways 18 for the key-operable tumblers. The key 15 has a longitudinal groove 15^a at one side thereof for receiving the lugs as it is inserted into the key slot 14. A stud 25 is connected eccentrically to the inner or rear end of the plug. This stud is adapted to be connected to a bolt 75 or locking element and operates upon rotation of the plug into its locked position to throw the bolt for locking purposes.

The special tumbler 17 is disposed at the inner or rear end of the plug and operates so to prevent axial displacement of the plug after insertion of the latter into the casing. It is preferably stamped from plate metal and is mounted slidably in a transversely extending slideway 26. The latter is formed 85 in the inner or rear end of the plug and is arranged so that the tumbler 17, when shifted outwardly, engages the annular shoulder 13 that defines the front end of the recess 12. The special tumbler is forced outwardly 90 into engagement with the shoulder by means of a spring 27. This spring is disposed in a socket 28 at one side of the slideway 26 and abuts against an ear 17^a which projects laterally from and is formed integrally with 95 the tumbler 17. The central portion of the special tumbler is provided with a slot 29 for receiving the end of a special key (not shown) of the character specified in an application for Letters Patent of the United States filed by me May 19, 1930, and serially numbered 453,431. The special key is somewhat longer than the regular key 15 and operates when inserted into the plug and the plug is in its unlocked position to depress 100 the special tumbler so that the plug may be withdrawn from the casing for repair or replacement purposes.

To prevent ejection of the tumblers from the slideways 18 by the springs 19 110 when the plug is withdrawn from the casing and the key 15 is removed from the key slot 14, tongues 30 are formed on the tumblers. These tongues coact with the guide lugs 24 and are formed by striking outwardly the inner parts of the end bars 16^c during stamping of the tumblers. In assembling the lock the key-operable tumblers 16 are inserted into the slideways 18. Insertion of the tumblers into the slideways is 115 effected by placing the end bars 16^c into engagement with the slideways and then forcing the tumblers downwardly so that they are disposed in their operative position. During the initial shift of the tumblers into 120 place, the outwardly projecting tongues 30 engage the guide lugs 24 and are forced inwardly. After being forced past the lugs, the tongues spring outwardly into a position 125 wherein they coact with the lugs to hold the 130

tumblers in connected relation with respect to the plug and against ejection by the springs when the plug is removed from the casing and the key is withdrawn. The tongues are so formed that the tumblers 16 have limited sliding movement within the slideways 18 and are free to be forced outwardly by the springs 19 into a position wherein the end bars 16^b are disposed in the groove 22 or the groove 23. By utilizing the guide lugs 24 for abutments for the tongues, the construction is simplified. The special tumbler 17 is held in connected relation with respect to the plug and is prevented from being ejected when the plug is withdrawn from the casing by means of a tongue 31. This tongue is similar in construction to the tongues 30 on the key-operable tumblers and cooperates with the inner or rearmost guide lug 24, as illustrated in Figure 2.

In assembling the lock, the special key is used to depress the tumbler 17 and the plug with the special tumbler in its depressed position is inserted into the casing 7. Upon removal of the special key from the key slot 14 in the plug the spring 27 forces the special tumbler outwardly into engagement with the annular shoulder 18. Rotation of the plug in the casing is effected by inserting the regular key 15 into the key slot 14 so as to shift the tumblers into a position wherein the end bars 16^b and 16^c are aligned with the inner periphery of the casing. When it is desired to repair or replace the plug 8, said plug is first shifted into its unlocked position and then is removed from the casing by use of the special key. Upon removal of the special key, the key-operable tumblers 40 and the special tumbler are shifted outwardly by the springs 19 and 27. Ejection of the tumblers, however, is prevented by the tongues 30 and 31 which engage the guide lugs 14 as previously pointed out and thus limit outward movement of the tumblers.

The lock herein disclosed consists of but a comparatively small number of parts and therefore may be manufactured at a low cost. In view of the fact that provision is made for holding the tumblers in connected relation with respect to the plug and against ejection from the slideways, the plug may be removed from the casing without danger of losing the tumblers or springs.

The invention is not to be understood as restricted to the details set forth, since these may be modified within the scope of the appended claims, without departing from the spirit and scope of the invention.

Having thus described the invention, what I claim as new and desire to secure by Letters Patent, is:

1. In a lock, the combination of a casing having a bore extending longitudinally therethrough, a plug rotatable in and re-

movable from the bore and having formed therein a longitudinal slot for a key and a series of transverse slideways intersecting the slot, spring pressed substantially flat tumblers mounted slidably in the slideways and adapted to lock the plug against rotation in the casing, said tumblers being formed of metal stampings and having central slots therein through which the key may be inserted in order to shift the tumblers into an inoperative position, and tongues projecting outwardly from the face portions of the tumblers and lengthwise of the key slot and plug and arranged to engage and coact with parts of the plug to hold the tumblers in connected relation with the plug and prevent ejection upon removal of the plug from the bore.

2. In a lock, the combination of a casing having a bore extending longitudinally therethrough, a plug rotatable in and removable from the bore and having formed therein a longitudinal slot for a key, spring-pressed tumblers for locking the plug against rotation in the casing mounted movably in the plug and having central slots therein through which the key may be inserted in order to shift the tumblers into an inoperative position, and tongues on the key-engaged portions of the tumblers arranged to engage and coact with parts of the plug to hold the tumblers in connected relation with the plug and prevent ejection upon removal of the plug from the bore.

3. In a lock, the combination of a casing having a bore extending longitudinally therethrough, a plug rotatable in and removable from the bore and having formed therein a longitudinally extending slot for a key, lugs in the plug for guiding the key in the slot, spring-pressed key-operable tumblers mounted movably in the plug and adapted to lock said plug against rotation in the casing, and means on the tumblers adapted to engage and coact with the guide-lugs to hold the tumblers in connected relation with the plug and prevent ejection upon removal of the plug from the bore.

4. In a lock, the combination of a casing having a bore extending longitudinally therethrough, a plug rotatable in and removable from the bore and having formed therein a longitudinally extending slot for a key, lugs in the plug for guiding the key in the slot, spring-pressed key-operable tumblers mounted movably in the plug and adapted to lock said plug against rotation in the casing, and tongues on the key-engaging portions of the tumblers adapted to engage and coact with the guide-lugs to hold the tumblers in connected relation with the plug and prevent ejection upon removal of the plug from the bore.

5. In a lock, the combination of a casing having a bore extending longitudinally

therethrough, a plug rotatable in and removable from the bore, said plug having formed therein a longitudinally extending key slot and a series of transverse slideways intersecting the slot, lugs in the plug and between the slideways for guiding the key in the slot, spring-pressed key-operable tumblers mounted slidably in the slideways and adapted to lock said plug against rotation in the casing, and tongues on the tumblers arranged to engage and coact with the lugs to hold the tumblers in connected relation with the plug and prevent ejection upon removal of the plug from the bore.

10 6. In a lock, the combination of a casing having a bore extending longitudinally therethrough, a plug rotatable in and removable from the bore and having formed therein a longitudinally extending slot for a key, lugs in the plug for guiding the key in the slot, key-operable tumblers mounted movably in the plug and adapted normally to lock said plug against rotation in the casing, a spring-pressed device for holding the plug against axial displacement in the casing, mounted in the plug and releasable so that said plug may be removed from the bore, and a tongue on the element arranged to engage and coact with one of the guide lugs to hold the element in connected relation with the plug and prevent ejection upon removal of the plug from the bore.

15 7. In a lock, the combination of a casing having a bore extending longitudinally therethrough, a plug rotatable in and removable from the bore and having formed therein a longitudinally extending slot for a key, tumblers for locking the plug against rotation in the casing, mounted movably in the plug, operable by the key, a special spring-pressed tumbler for holding the plug against axial displacement in the casing, mounted movably in the plug and adapted by means of a special key inserted through the slot to be rendered inoperative so that the plug may be removed from the bore, and a tongue on the special tumbler arranged to engage and coact with a part of the plug to hold said special tumbler in connected relation with the plug and prevent ejection upon removal of the plug from the bore.

20 55 Signed at Chicago, Illinois, this 17th day of July, 1930.

LYLE B. SHINN.
